UNITED STATES PATENT OFFICE.

HENRY T. HILL, OF MANCHESTER, NEW HAMPSHIRE.

ELECTRIC SIGNAL.

SPECIFICATION forming part of Letters Patent No. 388,869, dated September 4, 1888.

Application filed December 17, 1886. Serial No. 221,884. (No model.)

To all whom it may concern:

Be it known that I, HENRY T. HILL, a citizen of the United States, residing at Manchester, in the county of Hillsborough and State of New Hampshire, have invented certain new and useful Improvements in Electric Signals; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to an improvement in electric signals; and it consists in an electric signaling apparatus particularly adapted for use in establishing communication between the locomotive and the different cars of a railway-train, but which is also adapted to be used in establishing communication between the various rooms of a house, manufactory, shop, &c.

The object of the invention is to provide a system of signals which may be operated at any point throughout its extent, instead of confining the operation to certain specified points along the line, where buttons are located; and it consists in such a construction and arrangement of parts, as will be hereinafter fully set forth.

Hitherto it has been the common practice for the conductor of a railroad-train to communicate with his engineer by means of a cord running through the several cars and attached to a bell or gong in the cab of the engine. This cord is generally suspended from the top of the car by suitable appliances in such a manner that the conductor or other person wishing to communicate with the engineer might pull it; but this method has been found to be very unsatisfactory, for the reason that in long trains when the conductor happened to be in the rear of the train he could not ring the bell without great exertion in pulling up all the slack in the bell-cord. Furthermore, he was never certain that he had rung the bell until some responsive action on the part of the engineer—such as a whistle or a lessening of the speed of the train—indicated the fact. The old-style bell-cord thus described has in some measure been supplanted by electrical signals,

in a great majority of which, however, buttons are made use of to operate the signal. Supposing these buttons to be located in each end of the car, or supposing them to be situated at only two or three points in the car, the person desiring to ring the bell must traverse the distance intervening between himself and a button before he could do so. This often causes great inconvenience, and in many cases serious consequences follow. It is for the purpose of overcoming these disadvantages, so patent in the previous methods of communicating between conductor and engineer, that I have devised the signaling system herein set forth.

In the annexed drawings, illustrating my invention, Figure 1 is an outline representation of a couple of cars in a railway-train, showing the location of the bell in each car and their connecting cable. Fig. 2 is a detail view of two or more bells, batteries, and the wires composing the cable which connects the bells. Fig. 3 is a view showing one way of securing the connecting-cable to the switch. Fig. 4 is a side view of the same and showing the location of bell, battery, and switch within a box, which is shown in dotted lines. Fig. 5 shows another way of connecting the cable with the switch, and Fig. 6 is an end view of the same. Fig. 7 is a vertical section of my improved form of coupling. Fig. 8 is a horizontal sectional plan view, and Fig. 9 is an end view, of the same.

Like letters of reference indicate like parts. B represents a box, which is preferably used to contain a bell, battery, and switch. When the device is to be employed on a railway-train, one of these boxes is placed in each car. In Fig. 1 the location of the boxes is indicated. They are suspended from the top of the car by means of ornamental arms, in order to give the device a neat and tasty appearance; but it is obvious that they may be arranged in any manner and located in any part of the car. A cable, A, composed, preferably, of three wires, *a b c*, establishes communication between the bells within the several cars and the bell or bells within the cab. The cable has its several portions belonging to the several cars coupled together by means of any suitable and convenient coupling at *c*, so that when the

train is made up a continuous bell-cable throughout its whole length may be put into working order in a manner similar to connecting the parts of the ordinary bell-cord.

5 Within the boxes or bell-cases B is situated a bell and also the parts essential to accomplish the ringing of that bell. These parts usually consist of a switch, C, with which the cable A is connected, and also a battery of one or more cells.

Manifestly the entire battery may, if desired, be situated in the cab; but I generally prefer to have one or more cells situated near each bell or gong.

15 In Fig. 1 a switch, C, is seen projecting from the bottom of each box and having the cable attached to these projecting ends. This switch is pivoted at one of its ends in some suitable manner within the box, as at f, the other end 20 being free to be drawn to the right or left. The switch is kept normally in an upright position by means of springs. (Not shown.) The cables coming toward the end of the switch in each direction are connected with it 25 in some suitable manner and then turned up alongside of and across the same.

The cable in crossing the switch has the covering removed from its wires, so that they may be connected with screws or other devices secured upon the switch C. In Fig. 3 I have shown a representation of the switch as thus arranged, and Fig 4 is a side view of the same switch, and shows also the other contents of one of the boxes. One of the wires, as b, which is fastened to a screw upon the switch, passes from the screw to the battery. Another wire, as c, passes from the switch to the bell. Battery and bell are connected by a short wire, d. The connections of b and c with battery and bell are 30 permanently maintained, while the wire a is brought into the circuit when the switch is moved to the right or left. This other strand or wire, a, of the cable is affixed to a screw, which passes through a plate, E, having spring-like ends bent at right angles to its main portion, as is seen in Fig. 4.

45 The switch C is provided with a block or bar, D, of insulating material, such as vulcanized rubber, which holds the screws which connect with wires a b c. The screws for the wires a and c are fastened into the insulator alone, while the screw for the wire b passes through the insulator and into the switch-bar C. Thus the wire b connects with the battery and 50 also with the switch. The switch-bar C is further provided with studs or projecting pins g, on each side, as shown in Figs. 3, 4, and 5.

55 Adjustable stop-pins P are situated on each side of the switch, so as to limit its lateral swing. I have thus far been describing the construction of that form of switch shown in Figs. 3 and 4. In Figs. 5 and 6 is shown a slight modification. The stop-pins P are located on opposite sides of the free end of the switch, instead of on opposite sides of the middle, and consequently the spring-plate E and the studs g, are located at the end. Fur-

ther, the cable does not meet the switch at the end, but near the middle. In such a case as this it would pass through apertures in the 70 sides of the box B, and all the accompanying mechanism of the switch would be concealed, instead of having the bar C project through the bottom.

75 The operation of the device as thus described is as follows: When the cable A is pulled at any point, the switch C will be thrown over against one of the stop-pins P. This depresses the spring end of the plate E as it touches the pin P, so that said spring end comes into 80 contact with the projecting stud g on the switch-bar. Thus communication is established between the wire a and the wire b. In so doing the circuit is made complete, so that all the bells will ring both in the cars and in the cab. 85 It is obvious that the conductor if he hears the bell ring in one car can depend with certainty upon the fact that the bell has rung in the engine, for if one bell rings they must all necessarily ring, as they are all in the same circuit. 90

Many ways may probably be devised for carrying out the principle of my invention, and I have here recorded with minute particularity only one of those ways as illustrative of the principle.

95 The invention is as well adapted for houses, factories, &c., as for railway-cars, and the necessary variations of the system, as herein set forth, can easily be made without departing from the spirit of the invention.

100 If, from motives of economy or for other reasons, it be desired to dispense with the bells in the cars and ring only the one (or two) in the cab, it may be done without violating the spirit of my invention, although I believe the system as heretofore described with a bell in each car to present certain advantages. No alterations would be made save that the box which would contain the switch would be smaller, since it would not also inclose a bell and cell.

105 Figs. 7, 8, and 9 illustrate my improved form of coupling for the cables at points between the cars. It may be made of metal or hard rubber, and consists of shells X, containing two or three springs, x x x, which are connected with the wires of the cable by screws or other devices. A thimble or collar, Y, is screwed or otherwise fastened to the shell X, so as to cover the wires, screws, and rear ends of 110 the springs, which may be packed with some water-proof material which will protect the wires from any dampness. The outer flange of the shell is grooved to receive a rubber packing, x'. The springs x are made with 115 bevels y in such a manner that any other coupling may be connected by a simple sliding together of the two beveled sides of the springs, and the inside bevel is sharper than the outer bevel, as shown, so that when together the 120 tendency when the cable is being pulled is to draw the parts of the coupling closer instead of to loosen it. It may, however, be easily separated, and in case the train should be broken

apart the springs would be sufficient to give the alarm before separating the coupling.

Having thus described my invention, what I claim as new, and desire to secure by Letters

5 Patent, is—

1. An electrical signaling apparatus consisting of an electrical circuit, including electric bells connected by a triple-wire cable whose wires are attached to circuit-closing 10 switches, two of the wires being permanently connected with the batteries and bells, said circuit being normally open but adapted to be closed to ring the bells by a pull upon the cable which oscillates the switches and brings 15 the third wire into circuit, substantially as described.

2. An electric signaling apparatus consisting of the combination, with electric bells, of circuit-closing switches and a triple-wire cable connecting said switches, two of the wires being permanently connected with the batteries and bells, while the third is brought into the circuit when the switch is moved, and all the parts being arranged and adapted to be operated 20 manually by a pull upon the cable at any point throughout its length, so as to ring all the bells in the circuit, substantially as shown and described.

3. In an electric signaling apparatus, the combination of a triple-wire cable, pivoted switch-bars, with which the exposed wires of the cable are severally connected, a battery connected with each switch by a wire passing to one of the cable-strands, and bells connecting with each switch by a wire to another cable-strand, all arranged and operating in such 35 a manner that a pull upon any part of the

cable will move the switch and connect the current passing through the last cable-strand with the current passing to battery, substantially as shown and described. 40

4. In an electrical signaling apparatus, the combination, with a battery and a bell, of a pivoted switch-bar and a triple-wire cable attached to said bar in such a manner that two 45 of its wires may be permanently connected with the battery and bell, respectively, while the third is adapted to be brought into the circuit by a pull upon the cable and a consequent movement of the switch-bar, substantially as 50 described.

5. In an electrical signaling apparatus, the combination of a triple-wire cable, a pivoted switch-bar provided with an insulating-block, the holding-screws in the insulating-block to 55 which the cable-wires are connected, two of said screws being fastened into the insulator alone, while the third passes through it into the switch-bar, and a connected battery and bell, the battery being permanently connected 60 with that one of the wires whose holding-screw enters the switch, and the bell being permanently connected with one of the wires whose holding-screw is in the insulator alone, while the third wire is arranged to be brought into 65 the circuit to ring the bell by a pull on the cable, whereby the switch is oscillated, substantially as described.

In testimony whereof I affix my signature in presence of two witnesses.

HENRY T. HILL.
